UNITED STATES PATENT OFFICE.

OLIVER P. WILLIAMS, OF YOUNGSTOWN, FLORIDA, ASSIGNOR OF ONE-THIRD TO
ARTHUR C. WILLIAMS, OF MURDOCK, FLORIDA.

RAILWAY-RAIL.

1,231,465.

Specification of Letters Patent. Patented June 26, 1917.

Application filed February 20, 1917. Serial No. 149,849.

To all whom it may concern:

Be it known that I, OLIVER P. WILLIAMS, a citizen of the United States, residing at Youngstown, in the county of Bay and State 5 of Florida, have invented new and useful Improvements in Railway-Rails, of which the following is a specification.

The present invention relates to improvements in the construction of railways rails.

10 In carrying out my invention it is my purpose to produce a compound rail of a comparatively simple, cheap but thoroughly efficient construction whereby the joints between the tread portion of the rails will be 15 broken with respect to the joints of the base or supporting portions of the said rails and also wherein the said base or supporting portions comprise substantially similar but independent members arranged upon the opposite sides of the web of the tread portion of the rail and interlocking with the said web, and whereby the joints or the meeting ends of the said base or supporting members will not be disposed opposite each other, so 20 that the staggered joints between the supporting and the tread portions of the rail tends to produce a substantially continuous rail.

With the above and other objects in view 30 the improvement resides in the construction, combination and arrangement of parts set forth in the following specification and falling within the scope of the appended claim.

In the drawing:

35 Figure 1 is a side elevation of a compound rail constructed in accordance with the present invention,

Fig. 2 is a transverse sectional view through the same taken upon a greatly enlarged scale,

Fig. 3 is a horizontal sectional view upon an enlarged scale and approximately on the line 3-3 of Fig. 1,

40 Fig. 4 is a detail perspective view of the tread member of the rail, and

Fig. 5 is a similar perspective view of one of the base or tread supporting members.

45 The rail is broadly indicated by the characters R and the supporting ties by the characters T.

The rail includes tread members all of a similar construction, each comprising a head 1 and a centrally arranged depending web 2. The web at the lower edge thereof is formed 55 with outwardly extending angularly dis-

posed ribs 3-3 so that the said lower edge of the web is substantially V-shaped in cross section.

The head 1 of the tread of the rail upon its underface and in a line with the sides of the web 2 is formed with continuous V-shaped channels 4-4, and the web between the ribs 3 and the underface of the ball or head of the rail is provided at spaced intervals with transverse bolt openings. The base or support for the tread comprises 60 members adapted to be disposed at the opposite sides of the tread and are of similar construction. Each of the base or supporting members includes a straight plate or 65 side member 5, the upper edge of which being beveled, as at 6, whereby to be received in the channels 4 in the underface of the head or ball of the tread portion of the rail. The plates or side members 5 are provided with 70 openings 7 that are designed to register with the openings in the web of the tread and the said plates 5 below the said openings are formed each with an outwardly extending 75 flange 8, the inner surface of which corresponds to the outer angular surface of the ribs 3 upon the web 2 of the tread. The outer edges of the flanges 8 may be notched 80 whereby to receive spikes 9 that enter the ties T, and formed with the flanges 9 are 85 inwardly extending flanges 10, the same being formed with a continuous upwardly projecting rib 11, the outer edge of the said flange being vertically straight and the angular inner face of the said ribs 11 being 90 designed to engage with the angular surfaces of the ribs 3 upon the web 2 of the tread. The straight inner edges of the base 10 upon the side members of the support 95 may contact, and when the securing elements are passed through the alining openings in the plates 5 and in the web 2 of the tread sections of the rail, and the nuts screwed upon the said bolts, the sections comprising the rails may be readily associated in a firm and substantial manner whereby the tread 100 surface is effectively supported upon the base members of the rail. It will be apparent by reference to the drawings and from the above description that the meeting ends of the side members of the support may be disposed a suitable distance away from the meeting ends of the tread members and also 105 that the meeting ends of the supports on one of the sides of the rails may be disposed 110

away from the meeting ends of the supports upon the opposite sides of the rails.

Having thus described the invention, what I claim is:

- 5 In a compound rail, a tread including a head and a web centrally depending from the head, said web upon its lower edge having outwardly extending angularly disposed ribs, the head of the tread upon its underface being grooved longitudinally in a line with the sides of the web, a support for the tread comprising plates adapted to engage with the sides of the web and to have their upper edges received in the underface of the

head of the tread, said plates having their lower portions flanged outwardly to engage with the outer surfaces of the ribs upon the web, said plates having their lower edges provided with inturned members that have their inner edges formed with upwardly extending ribs that are adapted to engage with the underfaces of the ribs of the web and to contact with each other, and means comprising transverse members passing through the side members and webs for connecting the said sides to the webs of the rails.

In testimony whereof I affix my signature.

OLIVER P. WILLIAMS.

Copies of this patent may be obtained for five cents each, by addressing the "Commissioner of Patents, Washington, D. C."
